[57] CLAIM

The ornamental design for a trash container top, as shown and described.

DESCRIPTION

FIG. 1 is a top and front perspective view of a trash container top showing our new design, the broken lines are for illustrative purposes only and form no part of the claimed design;

FIG. 2 is a top plan view thereof;

FIG. 3 is a front elevational view thereof.

FIG. 4 is a left side elevational view thereof.

FIG. 5 is a bottom plan view thereof.

FIG. 6 is a rear elevational view thereof.

FIG. 7 is a right side elevational view thereof.

FIG. 8 is a cross sectional view thereof taken along the line 8—8 of FIG. 2. A portion of the top is shown broken away for convenience of illustration.

FIG. 1

FIG. 5

FIG. 6

FIG. 7

FIG. 8
